UNITED STATES PATENT OFFICE.

ADOLPH F. CHRISTMAS, OF EASTON, PENNSYLVANIA, ASSIGNOR TO INGERSOLL-RAND COMPANY, OF JERSEY CITY, NEW JERSEY, A CORPORATION OF NEW JERSEY.

GOVERNOR FOR STEAM-ENGINES.

1,373,866.

Specification of Letters Patent.

Patented Apr. 5, 1921.

Application filed July 14, 1919. Serial No. 310,737.

To all whom it may concern:

Be it known that I, ADOLPH F. CHRISTMAS, a citizen of the United States, residing at Easton, in the county of Northampton and State of Pennsylvania, have invented a certain new and useful Improvement in Governors for Steam-Engines, of which the following is a specification.

This invention relates to a speed governor adapted to be applied to steam or other engines to maintain a constant speed under various conditions of load.

The objects of the present invention are to provide a simple, easily manufactured governing mechanism adapted to be readily applied to a fly wheel provided on the engine, which may be readily adjusted by movement of a weight and adjustment of a spring to adjust the engine to operate at different speeds.

A further object of the invention is to provide the stud upon which the governor weight is adapted to oscillate with a suitable amount of frictional resistance to this oscillatory movement so that when the engine is operated at fairly low speeds, say from 100 to 170 R. P. M. the effect of gravity upon the movements of the weight will be obviated.

With these and other objects in view, my invention consists in the features of construction and operation set forth in the following specification.

In the drawings annexed hereto and forming a part hereof:

Figure 1 shows a front elevation of the complete mechanism forming the speed regulating means.

Fig. 2 is a cross sectional view taken upon lines 2—2 of Fig. 1.

Referring more particularly to the figures of the drawing, the fly wheel is shown at 1 and the main shaft of the engine is shown at 2. The fly wheel 1 in the instance shown is provided on the outer end of the main shaft as is usually the case in the form of shaft governor for which the present invention is particularly adapted. At 3 is shown a stud or pin outstanding from one of the arms of the fly wheel 1, upon which pin a governor body 4 is adapted to oscillate. The governor body 4 is provided with a split portion at 5 and is suitably bored to receive the arm 6 of the governor weight 7. Suitable bolts

are provided through the split portion 5 of 55 the body 4 as shown at 8 so that the weight 7 may be securely fastened to the body 4 in any desired position and distance from the pin 3. A spring 9 is also attached at one end to the governor body 4, the other end 60 being made fast to a suitable fastening in one of the other arms of the fly wheel as shown at 10. A link 11 is pivotally mounted at one end on the governor body 4 and at its opposite end is connected to an eccentric 65 arm 12. On the arm 12 a pin 13 is provided to which pin 13 the valve rod 14 is attached in the usual manner.

From the above description it will be obvious that with the different speeds of the 70 fly wheel 1 and different tensions on the spring 9 the weight 7 will take a definite position due to the centrifugal force and the tension of spring 9, the position of the weight 7 determining the position of the eccentric pin 13 and thus the throw of the 75 valve rod 14. The variations from the speed desired will vary the position of the weight 7 and thus the position of the pin 13, thus increasing or decreasing the supply 80 of steam to the engine in the usual manner.

The mechanism above described is not a balanced one as is sometimes used in this form of governing mechanism. The weight 7 therefore when traveling upward during 85 one half of the revolution of the fly wheel will be slightly retarded by the effects of gravitation and when moving downward during the other half of the revolution of the engine its speed will be slightly accelerated 90 also due to the force of gravity. In order to obviate the effects of this action on an unbalanced governor a certain amount of friction is introduced to retard the oscillation of the governor body 3 so that there will be 95 a constant lag in the movement of the weight 7 about the pin 3.

In Fig. 2 a method of applying an adjustable friction to these parts is shown. It is to be understood, however, that any other 100 suitable manner of applying friction to these parts may be carried out within the spirit of my invention.

A bolt or rod 15 extends through the pin 3 throughout its entire length. Beneath the 105 head 16 of the pin 15 a collar 17 is provided and between the collar 17 and the front face of the governor body 4 any suitable friction

material 18 may be applied. This may conveniently be of any fibrous material as for instance a sheet of heavy fibrous paper. Also a similar sheet of friction material 19 5 may be provided between the rear surface of the governor body 4 and the front face of the fly wheel 1. On a rear surface of the fly wheel 1 a collar 20 is provided surrounding the bolt or rod 15 against which presses 10 a spiral spring 21. At the outer edge of the spring 21 a plate or washer 22 is provided pressing against the nut 23. Adjustment of the nut 23 will increase the pressure of the spring 21 and thus increase the frictional 15 resistance to movement of the casting 4 about the pin 3.

Having thus described my invention:

1. In a governor for steam engines, the combination with a fly wheel, of a hollow pin mounted in one arm of the fly wheel, a bolt passing longitudinally through said pin, a governor body pivoted on said pin, a governor arm carried by said body, a governor weight adjustable to and from the said 20 pin about which the weight is adapted to oscillate, a collar on said bolt and friction material between said collar and the face of the said governor body, for withstanding the accelerating effect of gravity as the weight travels with gravity, and friction material between the fly wheel arm and the inner face of said fly wheel body. 25

2. In a governor for steam engines, the

combination with a fly wheel, of a hollow pin mounted in one arm of the fly wheel, a bolt passing longitudinally through said pin, a governor body pivoted on said pin, a governor arm carried by said body, a governor weight adjustable to and from the said pin about which the weight is adapted to oscillate, a collar on said bolt and friction material between said collar and the face of the 35 said governor body, for withstanding the accelerating effect of gravity as the weight travels with gravity, and friction material between the fly wheel arm and the inner face of said fly wheel body. 40

3. In a governor for steam engines, the combination with a fly wheel, of a hollow pin mounted in one arm of the fly wheel, a bolt passing longitudinally through said pin, a spring adapted to be compressed beneath 50 one end of the bolt, a governor body pivoted on said pin, a governor arm carried by said body, a governor weight adjustable to and from said pin about which the weight is adapted to oscillate, and friction material 55 pressed against one face of the governor body by the bolt, for withstanding the accelerating effect of gravity as the weight travels with gravity.

In testimony whereof, I have hereunto set 60 my hand.

ADOLPH F. CHRISTMAS.
